UNITED STATES PATENT OFFICE.

GEORGE W. BOWER, OF SCHENECTADY, NEW YORK, ASSIGNOR TO GENERAL ELECTRIC COMPANY, A CORPORATION OF NEW YORK.

SECTION INSULATOR.

Application filed November 23, 1923. Serial No. 676,666.

To all whom it may concern:

Be it known that I, GEORGE W. BOWER, a citizen of the United States, residing at Schenectady, in the county of Schenectady, 5 State of New York, have invented certain new and useful Improvements in Section Insulators, of which the following is a specification.

The present invention relates to overhead current conductors for electric railways and more especially to section insulators whereby a system of overhead wires is provided with definite points of division electrically so that any section may be cut out from the 15 current supply, and rendered dead and safe for repairmen to work upon, etc., while the remainder of the system continues in condition for normal operation.

Practically all trolley systems in use at 20 the present time require the overhead trolley wire to be tightly stretched, under a tension of one thousand to three thousand pounds, and to be yieldingly supported in the vertical plane so that upon passage of the current collector, pressing upwardly against the under side thereof with a force of twenty-five to thirty pounds, substantially all the irregularities and variations in height of the wire will be uniformly overcome by its freedom of movement vertically and in this way avoid or greatly minimize vibration or vertical swing of the trolley head which ordinarily at high speeds tends to jump from one point of low elevation to the next and in so doing causes injurious 25 arcing between itself and the wire.

Whenever a body, such as a section insulator, is applied to an overhead conductor it, by reason of its relatively greater inertia, 30 acts as a dead weight thereon and seriously interferes with the uniform floating or wave motion normally produced in the yieldably supported conductor upon the passage of the trolley. On account of the severe hammer blows a trolley strikes such a body applied to an overhead conductor when traveling at speed, it is common practice to bring an electric street car almost to a stop as its trolley passes a circuit breaker 35 and it is also common practice to disconnect the car circuit until the section insulator is passed in order to avoid injurious arcing.

On electrified steam railways and other 40 systems where long heavy trains are

operated at speeds of a mile per minute, the current collector is of the slider or pantographic type and possesses relatively great inertia and in consequence of which the hammer blows resulting from the presence 45 of any dead weight on the wire are excessive. Moreover, the troubles and expense incidental to the slowing up of such a train to enable the trolley to pass the section insulators quietly are too great to be tolerated 50 by railway operators. The object of my invention is to provide an improved section insulator which will operate satisfactorily under severest operating conditions, which will be hardy and durable, and which may 55 be easily and quickly repaired by ordinary workmen.

One embodiment of the invention is shown in the accompanying drawing, in which Fig. 1 is a top plan view of my section insulator, and Fig. 2 is a side elevation thereof.

The main frame of the device is generally H-shaped and consists of a longitudinal metal bar 1, preferably made tubular for 60 the sake of lightness, with a cross or spreader bar 2 rigidly connected, as by welding, to each end thereof. The outer ends of the cross bars 2 are provided with lugs 3 whereby the device may be attached 65 to suspension wires. On each arm of the cross bars 2 is mounted a spool insulator 4 having a series of annular corrugations 5 on opposite sides of a cylindrical center portion 6. Metal brackets 7, 8, 9, and 10 having circularly recessed heads are attached to the cylindrical center portions 6 by clamping plates 11 and bolts 12 and are thus electrically insulated from the frame.

The brackets 8 and 10, at the rear left and front right-hand corners of the frame as shown in Fig. 1, are in the form of vertical posts with three cross pins or points of attachment 13, 14 and 15 at the lower ends thereof. The other brackets 7 and 9 have three attachment ears 16, 17, and 18, arranged substantially radial to the axis of the respective cross bar 2.

The trolley wire 19 is of course severed for the introduction of the section insulator and each of the severed ends is clamped to a strain block or coupling 20 adapted to be pinned to the respective post brackets 8 and 10 at the connecting points 15 and the tension of the trolley wire exerted thereon is 110

taken up by tie rods 21 extending diagonally upward from attachment points 13, opposite the attachments 15, to the attachment ears 18 on the respective brackets 7 and 9 and from these points the tension is taken up by anchor wires 22 interrupted by strain insulators 23 arranged in pairs. The opposite ends of the anchor wires 22 are attached to strain ears 24 secured to the trolley wire sections 19 a considerable distance, about fifteen feet, from the respective ends thereof so that the stresses exerted on the anchor wires 22 are on a line substantially parallel to the trolley wire. In order to provide trackage for the trolley beneath the insulator, a flexible conductor strip of hard drawn copper is bolted to each of the bracket arms 17 and bent downwardly on a long radius adjacent thereto, and then extended horizontally beneath the respective post bracket 10 by which it is supported flexibly by an ear 26 having a vertical slot 27 whereby it may move freely up and down a limited distance on the supporting pin 14, and beyond the ear 26 it is bent upwardly through a small angle to provide a gradual incline 28 to the trolley wire 19 to which it is attached by a guide ear 29 intermediate the points of attachment of the strain block 20 and the strain ear 24 thereto.

If it be assumed that a current collector of the pantograph type approach the section insulator from the right-hand, it will contact with the guide bracket 29, which being supported by a straight section of trolley wire is free to move upwardly without perceptible effect on the collector. Such lifting effect as the collector produces in passing beneath the guide ear 29 and the inclined portion of the track strip 25 operate to rock the section insulator about its longitudinal axis so as to depress the opposite track strip 25 into position to be engaged at its curved portion by the collector after the latter has traveled a considerable distance along the other track strip 25. During the time the collector is in contact with both strips it tends to restore the section insulator to its original position. Upon the departure of the collector from the rear end of the first track strip the section insulator begins to rock on its axis in the opposite direction and slightly elevates the end of the left-hand section of the trolley wire 19 so that it passes thereto without perceptible impact. In fact, it has been determined by actual use that each of the five points of changing contact is passed serially by the collector without perceptible shock or disturbance to the overhead structure or to the collector.

In case the flexible track strips 25 or their attachments should become worn, they may be removed and replaced without disturbing any other part of the insulator or the tension of the trolley wire. 65

While I have shown and described the best embodiment of the invention known to me, I do not desire to be restricted thereto.

What I claim as new and desire to secure by Letters Patent of the United States, is:—

1. A section insulator comprising a frame, two spaced conductor tracks supported at opposite sides thereof and each provided with a flexible inclined end having provision for attachment to the respective trolley wire sections, and attachment means for the ends of the trolley wire sections connected to said frame independent of said conductor tracks. 75

2. A section insulator comprising a frame, two spaced conductor tracks yieldably supported beneath the said frame and at opposite sides thereof and each provided at one end with a flexible inclined portion having provision for attachment to the respective trolley wire sections, and strain attachment means for the ends of the trolley wire sections connected to said frame independent of said conductor tracks. 85

3. A section insulator comprising a horizontal frame, two vertical post brackets supported at diagonally opposite corners thereof, means for attachment of the severed ends of a trolley wire to the respective brackets, insulated strain means connected to said brackets and to said frame for transmitting the tension of one trolley wire section to the opposed wire section, and two spaced conductor tracks of flexible material adapted to be connected to the respective trolley wire sections, to the respective brackets, and to the opposite ends of the frame. 95

4. A section insulator comprising an H-shaped frame having two vertical post brackets at diagonally opposite corners thereof and attachment brackets at the remaining corners, tie rods connecting the lower end of each post bracket with the attachment bracket on the respective sides of said frame, means for attachment of the ends of the trolley sections to said post brackets, and two flexible conductor tracks freely suspended from the lower ends of said post brackets and having the ends thereof detachably connected to the respective attachment brackets and to the respective trolley wire sections. 105

In witness whereof, I have hereunto set my hand this 22nd day of November, 1923.

GEORGE W. BOWER.
